UNITED STATES PATENT OFFICE.

JAMES S. SMART, OF CHICAGO, ILLINOIS.

SASH-HOLDER.

1,222,689.

Specification of Letters Patent.

Patented Apr. 17, 1917.

Application filed December 11, 1916. Serial No. 136,284.

To all whom it may concern:

Be it known that I, JAMES S. SMART, a citizen of the United States, residing at Chicago, in the county of Cook and State of Illinois, have invented certain new and useful Improvements in Sash-Holders, of which the following is a specification, reference being had to the accompanying drawings.

10 This invention relates to certain improvements in sash holders and has relation more particularly to a device of this general character of a wedge type; and it is an object of the invention to provide a novel and improved device of this general character which effectively serves to prevent the opening of a window sash or the like irrespective of the pressure or lifting force which may be imposed thereon.

15 Furthermore it is an object of the invention to provide a novel and improved device of this general character which includes a pivotally supported wedge member having coacting means for automatically adjusting 25 the same into an operative position.

A still further object of the invention is to provide a novel and improved device of this general character wherein the pivoted wedge member has coacting therewith means 30 to relieve the pivotal mounting thereof against strain or pressure whereby the strength and resisting power of the device is materially increased.

The invention consists in the details of 35 construction and in the combination and arrangement of the several parts of my improved sash holder whereby certain important advantages are attained and the device is rendered simpler, less expensive and 40 otherwise more convenient and advantageous for use, all as will be hereinafter more fully set forth.

The novel features of the invention will 45 hereinafter be definitely claimed.

45 In order that my invention may be the better understood, I will now proceed to describe the same with reference to the accompanying drawings, wherein—

50 Figure 1 is a fragmentary vertical sectional view illustrating a sash holder constructed in accordance with an embodiment of my invention and in applied position;

55 Fig. 2 is also a fragmentary vertical sectional view showing my improved sash holder in an inoperative position;

Fig. 3 is a view in perspective, from the

inside, of the wedge member as herein embodied;

Fig. 4 is a view in perspective of the casing as herein included; and

Fig. 5 is a view in top plan of my improved sash holder, detached.

As disclosed in the accompanying drawings, F denotes a window frame or the like, L a lower sash, U an upper sash, and P a parting strip interposed between said sashes L and U. The foregoing may be of any ordinary or preferred construction.

C denotes a casing of predetermined dimensions and which comprises a rear or back wall 1, the side walls 2 and a lower or bottom wall 3, and the back wall 1 is provided with suitable openings 4 through which screws 5 or other anchoring members may be directed for securing the casing at a point on the lower portion of the sash U which will best meet the requirements of practice. It is to be noted that the side walls 2 extend a predetermined distance above the upper edge of the back wall 1 and that said side walls 2 have in substantially horizontal alinement with the upper edge of the back wall 1 but adjacent the forward vertical margins of said side walls, the openings 6 in which are mounted the extremities of the pintle or bolt 7 for a purpose to be hereinafter referred to.

The side walls 2 are also provided adjacent the openings 6 with the horizontally disposed extensions 8 of a width in excess of the diameters of said openings and extending beyond opposite sides thereof, said extensions 8 being adapted to bend back upon the outer face of the side walls 2 to overlie the ends of the pintle or bolt 7 to hold said pintle or bolt against displacement and to strengthen said side walls 2.

W denotes the wedge member as herein employed and as disclosed in the accompanying drawings, said wedge member consists of the front wall or plate 9, the inwardly directed side walls 10, the inwardly directed top wall 11, and the inwardly directed bottom wall 12. The free longitudinal marginal portion of the top wall 11 is provided with the spaced sleeves or barrels 14 through which the pintle or bolt 7 is adapted to be directed and whereby the wedge member W is pivotally engaged with the casing C.

The wedge member W is of such a width as to have the walls thereof extend within

the casing C as is clearly set forth in the accompanying drawings.

Each of the free longitudinal margins of the sides 10 is disposed in different angles, 5 the upper angular portion *a* permitting an unobstructed upward movement to the sash L when the wedge member is in inoperative position as illustrated in Fig. 2 and the adjacent portion *b* is disposed on such an angle 10 as to contact with the shoulder 15 produced along the inner face of the adjacent side 2 of the casing C, whereby it will be at once self-evident that when the wedge member W is in applied position and force is 15 being imposed upon the sash L, the pintle or bolt 7 will be materially relieved from said force.

The adjacent marginal portion *c* is substantially parallel to the front wall or plate 20 9 and is defined by the inwardly directed and perpendicularly related wing or extension 16 adapted to afford a bearing surface over which the sash L will slide when said sash L is being raised or lowered.

25 The marginal portion *d* extends from the portion *c* to the outer end of the side wall and is arranged on such an angle as to rest against or contact with the back wall 1 of the casing C when the wedge member W is 30 in operative position.

It is to be noted that when the wedge member W is in operative position the lower end thereof terminates inwardly of the outer or free edge of the bottom wall 3 of the casing C so that it is rendered substantially impossible to engage the lower end portion of the wedge member from the outside of the frame F by an implement which would otherwise permit unauthorized lifting or upward movement being given to the wedge member W.

When it is desired to raise the sash L or to lower the sash U, the wedge member W is thrown upwardly to substantially a vertical position or until the same comes into contact with the sash U, as illustrated in Fig. 2 but as soon as the upper portion of the sash L passes below the pivoted end of the wedge member W, said member will be 50 automatically forced downward through the medium of the spring S.

The spring S as herein embodied comprises a substantially U-shaped member 17 which overlies the wall 11 when the wedge member W is in its substantially vertical or inoperative position, and the arms of said U-shaped member 17 terminate in laterally disposed and oppositely directed coils 18 encircling the pintle or bolt 7 and are continued by the extensions 19 which are anchored to the side walls 2 of the casing C. It is also to be noted that the coils 18 are positioned between the spaced sleeves or barrels 14 and that the adjacent portions of 65 the top wall 11 are cut out, as at 20, so that

the member 17 may properly coact with said wall 11 as has hereinbefore been set forth.

It is to be understood that my present invention is not intended to maintain the sashes L and U in a closed position with 70 their meeting rails substantially flush, but is adapted to be so arranged as to afford a predetermined relative movement of said sashes L and U as it is essential that the meeting ends of said sashes be in overlying relation 75 before my improved holder becomes effective.

It will also be readily understood that my improved holder is one that cannot be picked or forced open from the outside and 80 that its construction is such as to offset the action of a jimmy or other implements which may be used for a similar purpose.

From the foregoing description, it is thought to be obvious that a sash holder 85 constructed in accordance with my invention is of an extremely simple and comparatively inexpensive nature and is particularly well adapted for use by reason of the convenience and facility with which it 90 may be assembled, and it will also be obvious that my invention is susceptible of some change and modification without material departure from the principles and spirit thereof and for this reason I do not 95 wish to be understood as limiting myself to the precise arrangement and formation of the several parts herein shown in carrying out my invention in practice, except as hereinafter claimed.

100 I claim:

1. A holder of the character described comprising a member adapted to be engaged with a sash, a wedge member pivotally engaged with the first named member and capable of being swung upwardly and in vertical alinement with the member, and means for constantly urging said wedge member in a position to overlie the first named member, said first named member being provided 110 with a shoulder with which the wedge member contacts when at the limit of its movement toward the first named member.

2. In combination with an opening and relatively movable closure members for said opening, a casing secured to one of said members, a wedge member pivotally engaged directly with the casing and capable of being swung upwardly and in vertical alinement with the casing, and automatic means 120 for imparting movement to the wedge member in one direction, said wedge member when at the limit of its movement under automatic influence coacting with the second closure member for holding the same against 125 movement, said wedge member when at the limit of movement in an opposite direction permitting relative movement of said closure members.

3. In combination with an opening and 130

- relatively movable closure members for said opening, a casing secured to one of said members, a wedge member pivotally engaged with the casing, and automatic means 5 for imparting movement to the wedge member in one direction, said wedge member when at the limit of its movement under automatic influence coacting with the second closure member for holding the same against movement, said wedge member when at the limit of movement in an opposite direction permitting relative movement of said closure members, said wedge member being provided with inwardly directed bearing surfaces 10 with which the second named closure member is adapted to engage when said wedge member is in inoperative position.
4. A holder of the class described comprising a casing including outstanding side walls, a pintle supported by said side walls in proximity to an end of the casing and adjacent the outer margins of said walls, a wedge member including an inwardly directed end plate pivotally engaged with the 15 pintle and capable of being swung upwardly into vertical alinement with the casing, and automatic means coacting with said end wall of the wedge member for constantly urging the free end of the wedge member 20 toward the casing.
5. A holder of the class described comprising a casing including outstanding side walls, a pintle supported by said side walls in proximity to an end of the casing and adjacent the outer margins of said walls, a wedge member including an inwardly directed end plate pivotally engaged with the 25 pintle and capable of being swung upwardly into vertical alinement with the casing, and automatic means coacting with said end wall of the wedge member for constantly urging the free end of the wedge member 30 toward the casing.
6. A holder of the class described comprising a casing including outstanding side walls, a pintle supported by said side walls in proximity to an end of the casing and adjacent the outer margins of said walls, a wedge member including an inwardly directed end plate pivotally engaged with the 35 pintle and capable of being swung upwardly into vertical alinement with the casing, automatic means coacting with said end wall of the wedge member for constantly urging the free end of the wedge member toward the casing, shoulders carried by the side walls of the casing inwardly of the pintle, and side 40 walls carried by the wedge member to contact with said shoulders of the casing when the wedge member is in operative position.
7. A holder of the class described comprising a casing including outstanding side walls, a pintle supported by said side walls in proximity to an end of the casing and adjacent the outer margins of said walls, a wedge member including an end plate pivotally engaged with the pintle, automatic means coacting with said end wall of the wedge member for constantly urging the free end of the wedge member toward the casing, shoulders carried by the side walls of the casing inwardly of the pintle, and side 45 walls carried by the wedge member to contact with said shoulders of the casing when the wedge member is in operative position, the intermediate portions of said side walls of the wedge member being provided with inwardly directed wings to afford bearing surfaces.
8. A holder of the character described comprising a member adapted to be engaged with a sash, and a wedge member pivotally engaged directly with the first named member, and capable of being swung upwardly and in vertical alinement with the first named member, said first named member being provided with a shoulder with which the wedge member coacts when at the limit of its movement toward the first named member.
9. In combination with an opening and relatively movable closure members for said opening, a casing secured to one of said members, a wedge member pivotally engaged with the casing, said wedge member when at the limit of its movement toward the casing coacting with the second closure member for holding the same against movement, said wedge member when at the limit of its movement in an opposite direction permitting relative movement of said closure members, said wedge member being provided with inwardly directed projections having bearing surfaces with which the second named closure member is adapted to engage when said wedge member is in inoperative position.
10. A holder of the class described comprising a casing including outstanding walls, a pintle supported by said side walls in close proximity to an end of the casing and adjacent the outer margins of said side walls, a wedge member including an end plate pivotally engaged with the pintle, shoulders carried by the side walls of the casing inwardly of the pintle, and side walls carried by the wedge member to contact with said shoulders of the casing when the wedge member is in operative position, the central portions of said side walls of the wedge member being provided with inwardly directed wings to afford bearing surfaces.

42

11. A holder of the class described comprising a casing including outstanding side walls, a pintle supported by said side walls in proximity to an end of the casing and adjacent the outer margins of said walls, a wedge member including an end plate pivotally engaged with the pintle, shoulders carried by the side walls of the casing inwardly of the pintle, and side walls carried by the wedge member to contact with said shoulders of the casing when the wedge member is in operative position.

12. A holder of the class described comprising a casing including outstanding side walls, a pintle supported by said side walls in proximity to an end of the casing and adjacent the outer margins of said walls, a

wedge member including an end plate pivotally engaged with the pintle, shoulders carried by the side walls of the casing inwardly of the pintle, and side walls carried by the wedge member to contact with said shoulders of the casing when the wedge member is in operative position, the intermediate portions of said side walls of the wedge member being provided with inwardly directed wings to afford bearing surfaces.

In testimony whereof I hereunto affix my signature in the presence of two witnesses.
